(57) **CLAIM**

The ornamental design for a playset for use with modeling compound, as shown.

DESCRIPTION

FIG. 1 is a perspective view of the playset for use with modeling compound of the instant invention;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof; and,

FIG. 7 is a right side elevational view thereof.

The portions shown in broken lines are for illustrative purposes only and form no part of the claimed design.
